REGULATOR SYSTEM

Herbert Ziebolz, Chicago, Ill., assignor to Electronbeam, Ltd., Chicago, Ill., a partnership

Application November 22, 1943, Serial No. 511,332

4 Claims. (CL 318—28)

1

This invention relates to regulator systems for regulating various physical conditions such as temperature, pressure and the like. My invention is especially concerned with the use of a cathode ray tube in a regulator system designed to respond to variations in a given physical condition and to exercise control over apparatus tending to restore the condition to its original value or to a desired value.

In accordance with my invention, the electron beam of a cathode ray tube is deflected in response to changes in a condition to be regulated, and the deflection of the beam sets into operation a movable control element which acts to restore the condition to its original value. For the purpose of preventing overshooting of the regulating action, I provide means for generating a current or voltage having a value proportional to the speed of movement of the control member, and this variable current or voltage is applied to deflecting means tending to deflect the cathode ray beam in an opposite direction from the deflection caused by the change in the condition which resulted in movement of the control member.

One embodiment of my invention is illustrated in the accompanying drawing which is a circuit diagram illustrating a system for maintaining a constant pressure in a fluid supply system.

Referring to the drawing, 1 indicates a supply pipe for supplying fluid, such as gas or liquid, under pressure to any suitable apparatus represented at 2 and which requires a constant pressure of the fluid supply. It will be understood that the fluid pressure supplied to the apparatus is subject to change, either by reason of changes in the pressure of the source of fluid or by changes in the apparatus 2, and the problem is to maintain a constant pressure at the intake for the apparatus 2. For the purpose of regulating the pressure a control valve 3 is positioned in the pipe 1 and a suitable pressure responsive device 4 is connected to the pipe 1 between the valve 3 and the consuming apparatus 2. The device 4 responds to the pressure in the pipe 1 and produces a direct current or voltage in its output circuit 4a proportional to the pressure applied to the device. Such devices are well known and the details need not be described. The current produced by device 4 is employed to control the deflection of the beam of the cathode ray tube.

The cathode ray tube may be of any known construction, but for the purpose of illustration it consists of an insulating envelope 5 enclosing a filament 6 for heating the cathode 7 which

2

supplies electrons to form a cathode ray beam which passes through a perforated anode 8 which is maintained at a positive potential with respect to the cathode 7 by a source of potential represented by the battery 9. The cathode ray beam is represented by the dotted lines 10 and is directed towards target anodes 11 and 12 positioned in the opposite end of the tube from the cathode 7. Anodes 11 and 12 are maintained at a positive potential by suitable connections to source 9 through coupling resistances 11a and 12a. Beam deflecting means represented by a pair of deflecting plates 13 is provided for fixing the initial position of the beam, and these plates are supplied with an adjustable voltage from a suitable source represented by battery 13a through potentiometer 13b. The output of pressure responsive device 4 is connected to energize a second beam deflecting means represented by the coil 14, and this coil tends to deflect the beam in the opposite direction from plates 13. It will be understood that both deflecting means tend to shift the beam 10 from one target anode towards the other, and vice versa.

So long as the electron beam falls between target anodes 11 and 12, or where the beam falls upon the two anodes in equal amounts, there will be no difference of potential between the two target anodes. If, however, one target anode intercepts more electrons from the beam than the other, then a difference of potential develops between the anodes, and the polarity will depend upon which anode receives the greatest number of electrons.

An adjustable portion of the voltage developed across anodes 11 and 12 is applied between the grid elements of a pair of gaseous discharge tubes 16a and 16b by means of a potentiometer 15. The anode circuits of tubes 16a and 16b are energized from an alternating current circuit 17. The plate circuit for tube 16a includes a shaded pole winding 18a of a shaded pole motor 18, and the circuit for tube 16b includes the shaded pole winding 18b. The cathode return lead for both tubes 16a and 16b is connected to a common point which is connected to ground. The field winding 18c of motor 18 is energized from A. C. circuit 17. The field winding 18c of motor 18 is energized from A. C. circuit 17. Alternating current biasing potentials of the same phase and amplitude are supplied between the cathodes and the grid elements of tubes 16a and 16b from circuit 17 through potentiometer 20 and phase shifter 21, the circuits to the two grids being completed through high resistances 22a and 22b connected in series across the grid elements. The function of the A. C. biasing potential is to normally pre-

vent firing of tubes 16a and 16b in the absence of an input signal. The function of phase shifter 21 is to adjust the phase of the biasing potential with respect to the anode potentials so that the biasing potentials lead the anode potentials by slightly less than 180° and both tubes are in a critical condition for operation by a small input voltage from potentiometer 15. The phase shifter 21 overcomes the so-called "dead zone" of the tubes 16a and 16b as more fully described in the co-pending application of Paul Glass Serial No. 467,669, now Patent No. 2,386,677, dated October 9, 1945. It will be understood that when a voltage is impressed on the tubes 16a and 16b from potentiometer 15, one of the grids is biased positively while the other is biased negatively, and the tube with the positive bias becomes operative to cause operation of motor 18 in one direction. When the polarity of the input voltage reverses, the other tube operates and causes the motor to run in the opposite direction.

Motor 18 is connected to operate control valve 3 through any suitable driving mechanism represented by a pulley 18d mounted on the motor shaft 18e and operating through belt 3a to drive pulley 3b connected with valve 3. Motor shaft 18e also drives the armature of a small D. C. pilot generator 23 having a field winding 23a energized from a suitable source of current. Pilot generator 23 is connected through potentiometer 24 to a third beam deflecting means represented by the coil 25 which is arranged to deflect the beam 10 in a direction opposite to the direction of deflection which initially caused the motor 18 to operate.

Operation of the regulating system is as follows:

Potentiometer 13b is first adjusted to determine the value of the pressure to be maintained at the inlet of apparatus 2. The movable element of this potentiometer may be provided with a suitable scale graduated in terms of pressure. Deflecting plates 13 tend to deflect the beam in a direction to cause operation of motor 18 in proper direction to open valve 3. As the pressure in apparatus 2 builds up, the current in deflecting coil 14 produced by device 4 increases and tends to deflect beam 10 in an opposite direction to plates 13, and as soon as the pressure reaches the desired point, the beam 10 has been deflected back to its central or normal position between anodes 11 and 12. The beam will remain in this position so long as the pressure remains at the desired value. If the pressure varies from this value for any cause, there will be a change in current in deflecting coil 14 in response to the change in pressure, and the beam 10 will be deflected in a direction to energize motor 18 and operate the valve 3 in a direction tending to restore the pressure to the initial or desired value. As motor 18 begins to operate, pilot generator 23 generates a voltage proportional to the speed of the motor and energizes coil 25 in a direction tending to restore the beam 10 to its neutral position. As soon as the motor has attained the speed sufficient to restore the beam 10 to its neutral position, the gaseous tube controlling the motor ceases to fire and the motor slows down with a consequent reduction in the deflecting action of coil 25. If the pressure has not been restored to its normal value, beam 10 will again be deflected in a direction to reenergize motor 18 which will cause a further movement of the valve 3 in the same direction tending to restore the beam to its neutral position. From the fore-

going it will be seen that deflecting coil 25 causes the intermittent energization of motor 18 to produce movement of valve 3 in a direction to restore the pressure to its normal value. The intermittent energization of the motor will produce an average motor speed which is proportional to the amount of departure of the condition from the set or desired value. Accordingly, the motor speed will be relatively high at the beginning of the adjustment for any given departure of the condition from its normal value, and the speed will decrease as the value of the condition approaches the normal value, and this action tends to prevent overshooting of the regulator.

In case the pressure should change in an opposite direction from that described above, the motor 18 will be driven in an opposite direction, and the voltage supplied to deflecting coil 25 by pilot generator 23 will also be reversed in direction, and the operation will be the same as described above. It will be noted that the deflecting action of coil 25 is always in a direction to oppose the resultant deflecting action between deflecting plates 13 and deflecting coil 14.

It is not necessary to provide a separate deflecting means for the pressure setting potentiometer 13b, since it is possible to incorporate this control in the energizing circuit of one of the other deflecting means. For example, the magnitude-setting potentiometer may be connected in series with the coil 14 as shown at 13a' and 13b', or it may be connected in the circuit of coil 25 as shown at 13a'' and 13b''.

When the regulator system is employed for regulating temperature, the apparatus 2 might constitute a heater or burner supplied with fuel from pipe 1, and the device 4, instead of responding to pressure, would comprise a temperature responsive device, such as a thermocouple, arranged to respond to the temperature of the heater 2. It will be obvious that my control system may be employed for regulating other physical conditions than those specifically referred to herein.

The term "cathode ray tube" is used in a generic sense to designate an electron tube of the type embodying means for producing a relatively narrow beam of electrons which is deflectable with respect to one or more stationary receiving or target anodes.

I claim:

1. In a regulator system, the combination of a movable control element for varying the magnitude of a condition to be regulated, means for operating said control element including an electron beam relay, manually adjustable magnitude setting means including a first deflecting means establishing a beam deflecting field acting on the beam of said relay and tending to deflect the beam of said relay in one direction, a second beam deflecting means establishing a beam deflecting field acting on said beam and tending to deflect said beam in the opposite direction, and means for energizing said second deflecting means in accordance with the value of said condition, a third beam deflecting means establishing a beam deflecting field acting on said beam and tending to deflect said beam in opposition to said second deflecting means, and means for energizing said third deflecting means in accordance with the speed of movement of said control element.

2. In a regulator system, the combination of a movable control element for varying the magnitude of a condition to be regulated, means for operating said control element including an elec-

tron beam relay having beam deflecting means, means for establishing a beam deflecting field tending to deflect said beam in a direction to increase the value of said condition, said field being of a predetermined magnitude and independent of the value of said condition, means for establishing a second beam deflecting field of a value proportional to the value of said condition and in opposition to said first field whereby said beam is deflected in accordance with the resultant between said fields, and means responsive to the movement of said control element for establishing a third beam deflecting field to oppose the deflection of said beam by said resultant field and of a value proportional to the speed of movement of said control element.

3. In a regulator system, the combination of a movable control element for varying the magnitude of a condition to be regulated, means for operating said control element including an electron beam relay, magnitude setting means including a first deflecting means energized by a predetermined amount independently of the value of said condition and producing a field tending to deflect the beam of said relay in a direction to increase the value of said condition, a second beam deflecting means producing a field tending to deflect said beam in the opposite direction, means for energizing said second deflecting means in accordance with the value of said condition, a third means producing a beam deflecting field, and means for energizing said third beam deflecting means in accordance with the speed of movement of said control element and in a direction tending to oppose the resultant deflection produced by said first and second beam deflecting means.

4. In a regulator system, the combination of a movable control element for varying the mag-

nitude of a condition to be regulated, means for operating said control element including an electron beam relay having beam deflecting means, magnitude setting means comprising means for normally deflecting the electron beam of said relay in a direction to increase the magnitude of said condition, means responsive to the magnitude of said condition and acting on said beam deflecting means in opposition to the action of said magnitude setting means and thereby limiting the increase in said condition to a value determined by the setting of said magnitude setting means, and means controlled by movement of said control element for energizing said beam deflecting means in proportion to the speed of movement of said control element and in a direction tending to oppose the movement of said control element.
